UNITED STATES PATENT OFFICE.

JAMES H. RAND, OF NORTH TONAWANDA, NEW YORK.

ROTATABLE INDEX.

Application filed September 2, 1921. Serial No. 497,874.

To all whom it may concern:

Be it known that I, JAMES H. RAND, citizen of the United States of America, and resident of North Tonawanda, in the county 5 of Niagara and State of New York, have invented new and useful Improvements in Rotatable Indexes, of which the following is a specification.

This invention relates to a rotatable index, 10 and more particularly to such an index adapted to be secured to an appliance such as a telephone instrument in connection with which it is to be used.

In the accompanying drawings which 15 illustrate a preferred embodiment of the invention,

Figure 1 is a side elevation of the index attached to a telephone instrument;

Figure 2 is a front view of the index;

Figure 3 is an enlarged fragmentary cross section of the hub and adjacent parts; and

Figure 4 is a perspective view of one of the indexing sheets removed from the frame.

5 represents the hub which is preferably 25 made of a cylindrical piece of wood having a series of longitudinal slots 6 formed in its periphery. A series of radially disposed partitions 7 are mounted in the slots; each partition preferably consisting of a sheet of cardboard or the like having its inner margin 8 folded over to increase the thickness of the sheet and furnish a certain amount of springiness by which the partition may be held by friction, without other securement, 30 in slot 6. Surrounding the extremities of the partitions 7 is a peripheral, cylindrical cover 9 of transparent material such as sheet celluloid, which is made from a flat sheet bent around the ends of the partitions, 35 the meeting ends being fastened by eyelets, 40 10 or other suitable means.

The transparent celluloid cylinder is made to have a close sliding fit with the ends of the partitions and is held in place by friction 45 without other securement.

In each of the open ended compartments thus formed between the hub, the partitions and the cover, is an indexing sheet on which are displayed the lists of telephone numbers 50 or other notations constituting the subject matter of the index. These indexing sheets are individually removable, so that the inscription may be readily altered or the sheets replaced by new ones, and each sheet is folded on two parallel lines to form a middle section 11, substantially conforming in shape

to the surface of the hub 5 between partitions and bearing on the hub, and two leaf sections 12, 12, substantially conforming to 60 and bearing against the partitions 7. The inscriptions are placed on the inner surface of the indexing sheet, and it will be obvious that as the device is rotated the several leaves will be successively brought into the view 65 of the user through the transparent cover 9.

The device is journaled on a bracket which may be made of wire bent to form a stem 13 adapted for attachment to the post of a telephone instrument by a suitable clamp 14, 70 and a pair of arms or branches 15 having in-turned ends which form pivots engaging holes in the ends of the hub.

If the device is to be used for an index of more or less permanent character in which few if any changes are to be made, the inscription may be placed directly on the partition sheets 7 instead of upon the indexing sheets 12. The partitions themselves may be removed for this purpose if necessary, although somewhat less readily than the indexing sheets 12. 75

The structure provides an inexpensive, convenient and light indexing device of a "knock down" type which is easy to assemble and disassemble, pleasing in appearance 80 and well protected against soiling by the transparent celluloid cylinder.

I claim:—

1. A rotatable index comprising a cylindrical hub having longitudinal slots, radially disposed sheets mounted in said slots, and a transparent peripheral cover supported solely by the free extremities of the radial sheets. 85

2. A rotatable index comprising a hub, radially disposed partitions, a transparent peripheral cover, and indexing sheets removably held in the compartments formed by the hub, partitions and cover, each indexing sheet being folded to form a middle section and two leaf sections substantially conforming respectively to the surfaces of the hub and of the partitions of one of said compartments. 90

3. A rotatable index comprising a hub having longitudinal slots, radially disposed partitions mounted in said slots, a peripheral cylinder of transparent sheet celluloid, and removable indexing sheets in the compartments formed by the hub, partitions and cover, each indexing sheet being folded on parallel lines to form a middle section adapt- 100 105 110

ed to bear on the hub and two leaf sections resting against the partitions.

4. A rotatable index comprising a hub, radially disposed sheets mounted on the hub, and a transparent peripheral cover open at its ends embracing and supported solely by the free extremities of the radial sheets.

5. A rotatable index comprising a hub, radially disposed partitions, a transparent

peripheral cover open at its ends embracing 10 and supported solely by the free extremities of the radial partitions, and index sheets held in the compartments formed between the partitions and cover and removable through the open ends of the cover. 15

Signed by me at Boston, Massachusetts, this 31st day of August, 1921.

JAMES H. RAND.
